BOTTLE CAP

Melvin E. St. Clair, Warehouse Point, Conn., assignor to Plax Corporation, West Hartford, Conn., a corporation of Delaware

Application November 1, 1954, Serial No. 32,900

Term of patent 14 years

(Cl. D58—26)

FIG. 1

To all whom it may concern:

Be it known that I, Melvin E. St. Clair, a citizen of the United States, resident of Warehouse Point, county of Hartford, State of Connecticut, have invented a new, original, and ornamental Design for a Bottle Cap, of which the following is a specification, reference being had to the accompanying drawing, forming a part hereof.

Fig. 1 is a top plan view of a bottle cap embodying my new design;

Fig. 2 is a side elevational view of the bottle cap; and
Fig. 3 is a bottom view of the bottle cap.

I claim:

The ornamental design for a bottle cap, substantially as shown.
